CLOTHING BAG

Nathan Waterman, St. Paul, Minn., assignor of
one-half to Merton J. Stevens, St. Paul, Minn.

Application February 7, 1938, Serial No. 189,022

1 Claim. (Cl. 206—7)

My invention relates to improvements in garment bags, an object of the invention being to provide a simple, inexpensive and serviceable bag or paper or the like adapted to envelop a garment hung on an ordinary coat hanger, and one that by reason of its durability is capable of reuse following its initial application to a garment, as in a dry cleaning establishment, where the bag would be furnished for protecting the cleaned garment until required to be worn.

Another object of the invention is to provide a garment bag of the present nature, so constructed that a garment, on its hanger, may be readily placed within the bag and suspended, together with the enveloping bag, through the medium of the hook on said hanger.

A further object of the invention is to provide a bag, as above, the construction thereof being such that the bag may be readily closed over a garment enveloped therein and easily and securely fastened in a durable manner to exclude dust from the bag.

An additional object of the invention is to provide an inexpensive bag or envelope of paper or the like adapted to be folded upon itself to provide marginal closure flaps biased relative to the body proper and to supply fastening means of simple and durable construction and arrangement for releasably holding said flaps securely closed and for closing the opening about the hanger.

With the foregoing and other objects in view, which will appear in the following description, the invention resides in the novel combination and arrangement of parts, and in the details of construction hereinafter described and claimed.

In the drawing Fig. 1 is a front elevational view of a garment bag embodying my invention, the same being shown as secured closed, and with an intermediate transverse portion thereof broken away.

Fig. 2 is a rear elevational view of the bag illustrated in Fig. 1, the same being shown open, as for the application thereto or removal therefrom of a garment.

Referring to the drawing, wherein similar parts are designated by similar reference characters throughout the several views, it will be understood that the structure illustrated as an embodiment of my invention comprises a bag of sheet material, such as paper or the like of light and inexpensive construction. The body 10 of the illustrated bag is made from a sheet folded into the form of a flat tube, the longitudinal

edges thereof being overlapped, as at 11, and sealed together by means of a suitable adhesive at the back of the bag. This flattened tubular structure is preferably closed at the bottom thereof in any suitable manner, as by folding the lower 5 marginal portion 12 of the structure upon the body thereof and gluing or otherwise securing such folded marginal portion in place. The mouth of the bag freely receives a garment hung on an ordinary coat hanger 13. The upper marginal portion of the bag is marked along lines, preferably, as by score lines 14, defining lines-of-fold converging upwardly from the side edges of the bag to the upper edge thereof, said lines-of-fold being arranged to conform with the inclined 10 shoulder portions 15 of the hanger. The upper corner portions of the bag are adapted to be folded forwardly on the score lines 14, or otherwise demarcated lines, against the face of the bag. These corner portions of the bag constitute 15 biased flaps 16 which close the mouth of the bag, save for a limited central opening preserved to accommodate the shank 17 of the hanger hook 18.

Fastening means are provided for each of the 25 biased flaps 16, such means for each of said flaps including a fastening string 19 adhesively secured along one of its end portions to the overlying layer of the flap near the outer, wide end thereof, on a line at right angles to the line-of-fold of said flap, and throughout the greater 30 part of the width of the flap. Said fastening means further includes a fastening button 20 suitably secured to the front layer of the bag. This fastening button 20 is located in alignment 35 with the line of attachment of the fastening string 19 to the flap 16 and, consequently, occupies a relatively protected position further removed from the side edge of the bag than the locality of the attachment between said fastening string and flap. This disposition of the button 40 40 places it where it is comparatively free from impairment in the handling of the bag and such disposition of the button, in alignment with the line of attachment of the fastening string 19 to the flap 16, minimizes the possibilities of the 45 tearing of the fastening string from the flap. The fastening string 19 is satisfactorily secured to the flap 16 by means of a strip of adhesive tape 21 which is pasted over the string and to 50 said flap. The button 20 is satisfactorily secured to the front of the bag by stitching or otherwise suitably fastening the button to an adhesive patch 22 and, in turn, pasting the patch to the 55 bag.

The garment to be protected by my improved bag is hung on an ordinary coat hanger 13, the supporting hook 18 of which is caught over any convenient rail, hook or other supporting medium. 5 The bag is held open to receive the suspended garment and is passed upwardly about the same, the biased flaps 16 being thereafter turned downwardly on their lines-of-fold to close the mouth of the bag, except for the limited central space which accommodates the shank 17 of the hook 10 of said hanger. With the flaps 16 folded into their closed relationship, the free ends of their respective fastening strings 19 are wound around their respective fastening button 20 as indicated in Fig. 1. Thus, the garment, on its supporting hanger, is completely enveloped within the bag and effectively protected. The attachment of 15 the fastening strings 19 to the wide, outer end portions of the biased flaps 16, and the tightening of said strings between said flaps and their respective fastening buttons 20 on lines at right angles to their respective lines-of-fold, keep the flaps snugly closed and close the opening around the shank 17 of the garment hanger to provide a 20 dust proof bag and at the same time effectively preserving the connections between the fastening strings and flaps under strains tending to disturb the folded flaps or impair said connections. 25

Further, the positions of the fastening buttons 30 20, inset from the side edges of the bag, afford protection to said buttons against impairing strains that otherwise might be imposed upon them were they to be located more nearly adjacent to said side edges of the bag.

From the foregoing, it will be seen that my improved bag structure is particularly advantageous in that it may be of especially inexpensive construction, yet highly serviceable and durable in use. 5

Changes in the specific form of my invention, as herein disclosed, may be made within the scope of what is claimed without departing from the spirit of my invention.

Having described my invention, what I claim as new and desire to protect by Letters Patent is:

A dust proof reclosing bag for enclosing a garment carried upon a garment hanger, said bag comprising a flattened tubular structure closed at the bottom and open at the upper end to form a mouth through which a garment supported on a hanger may be inserted, the corner portions at the mouth of the bag being of double thickness and being foldable upon the body of the bag along converging lines to provide biased closure flaps and provide a close fitting opening in the bag through which the hanger extends, a holding device for detachably securing each flap in position, comprising a string having one end portion secured to the outer surface of the flap in its folded condition and a fastener secured to the body of the bag and to which the free end portion of the string may be detachably secured, said fastener being located adjacent the flap to cause the string when applied thereto to draw the flaps 20 toward the hanger and close the opening in the bag through which the hanger extends. 25 30

NATHAN WATERMAN.
